UNITED STATES PATENT OFFICE.

HENRY J. WESTOVER, OF MOUNT VERNON, NEW YORK, ASSIGNOR TO H. WARD LEONARD, OF BRONXVILLE, NEW YORK.

VARIABLE-SPEED AND REVERSING GEAR.

SPECIFICATION forming part of Letters Patent No. 709,690, dated September 23, 1902.

Application filed August 30, 1901. Serial No. 73,778. (No model.)

To all whom it may concern:

Be it known that I, HENRY J. WESTOVER, a citizen of the United States, residing at Mount Vernon, in the county of Westchester 5 and State of New York, have invented a certain new and useful Improvement in Variable-Speed and Reversing Gears, of which the following is a specification.

The object of my invention is to provide a simple and effective arrangement of gears and shifting mechanism for three speeds and a reversing connection for reversing the driving connection, preferably at a low speed.

A further object is to provide a speed-varying gear in which the high-speed connection will be a direct driving connection instead of through gearing, as is the case in the numerous forms of variable-speed gears heretofore proposed. By employing a direct driving connection for high speed no power is wasted in gearing, which is an objectionable feature of nearly all variable-gear mechanisms.

In carrying my invention into effect I employ three parallel shafts, two of which—the low and the intermediate speed shafts—being journaled on a reciprocating slide and the high-speed shaft being arranged between the low and intermediate speed shafts, but not 30 on the reciprocating slide. The low and intermediate speed gears have fixed positions relative to each other and are moved positively into and out of mesh by the slide. For reciprocating the slide I preferably provide a 35 shaft having an eccentric at each end working in bearings in the slide, and beveled pinions are provided for rotating said shaft. The eccentrics are arranged so that when either the low or intermediate speed gears are in

40 mesh the eccentrics will be on dead-centers and will serve as a locking means to prevent the slide from shifting, and hence these two speed gears are positively locked when in driving connection with the motor or driving shaft—that is, one set is positively locked in mesh, while the other set is positively locked out of mesh. The high-speed shaft is in two parts, which are disconnected and constitute the driving and driven members of the gear 45 when operating at low or intermediate speed, and the two parts of this shaft are placed in

operative connection by means of a jaw-clutch, which is operated by a pivoted lever held under spring tension for throwing the clutch into engagement. The engagement 55 and disengagement of the clutch is controlled by a cam-wheel which rotates with the shaft through which the slide is reciprocated. The shape of the cam-wheel is such that while shifting from the position of rest to low speed and 60 from low speed to intermediate speed the clutch controlling the high-speed connection is disengaged and in shifting from the intermediate speed to the high speed the clutch is allowed to engage. The reversing mechanism 65 comprises a set of friction-gears for each end of the high-speed shaft and preferably an intermediate gear, such as beveled pinions, for changing the direction of rotation. The reversing-shaft, which carries part of the friction-wheels and the reversing-pinions, is mounted in eccentric bearings provided with a rocker arm or lever, by means of which the reversing-shaft is slightly raised or lowered, whereby the friction-wheels are placed into 70 or out of engagement. The friction-wheels of the reversing-gear are arranged so as to give a reduced speed at the driven end of the main or high-speed shaft.

My invention is illustrated in the accompanying drawings, in which—

Figure 1 is a plan view and partial section of the speed-varying gears, the top or cover of the casing being removed; Fig. 2, a cross-section on the line 2 2 of Fig. 1; Fig. 3, a cross-section on the line 3 3 of Fig. 1; and Figs. 4 to 8, inclusive, are diagrammatical illustrations of the relative positions of the gears, starting from the position of rest to the position of high speed.

Referring to the drawings, A is the main driving-shaft, made up in two parts, one part constituting the driving end and which is connected with the driving-motor by any suitable form of coupling A'. The driving end 95 of main shaft A carries a sleeve a, splined thereto and provided with a pinion A² and one member B of a clutch adapted to engage the other member B' of the clutch and which member is formed integral with a sleeve a', provided with gears A³ and A⁴. This sleeve is keyed to shaft A⁵, which is the driven end 100

of the main shaft. A^2 is the driving-pinion of the variable-gear mechanism.

A^3 is the low-speed gear, and A^4 is the intermediate-speed gear. Clutch BB' is the high-speed driving connection, B being the movable element. Low-speed shaft or connection C is a sleeve carried by a rod c, secured in slides S. Sleeve C is provided with gear C' and pinion C², the former being arranged to mesh with pinion A^2 and the latter with gear A^3 .

D is the intermediate-speed shaft or connection, which is also in the form of a sleeve carried by rod d, mounted in the slides S. Sleeve d is provided with gear D' and pinion D², the former being arranged to mesh with pinion A^2 and the latter with gear A^4 . Slides S are placed between two guide-flanges s, and at one end of the slides are the eccentrics e, operated by shaft E to reciprocate the slide. Shaft E is journaled in suitable bearings secured to the gear-casing. Keyed on this shaft is a sleeve e', having a beveled pinion E', with which the beveled pinion E² meshes and whereby the shaft E is rotated in either direction. Beveled pinion E² is carried by an arbor e³, having a pinion e⁴, which meshes with rack E⁴. This rack is shifted by any suitable mechanism in either direction to rotate the shaft actuating the reciprocating slide S. Arbor e³ works in a bearing m, mounted within the casing M, which is secured over an opening in the top plate or cover of casing G, as shown in Fig. 2, an opening being provided at one side of casing M for the rack-bar E⁴. Sleeve e' is also provided with a cam-wheel E³, having a cam or recess e². The high-speed clutch B B' is operated by lever F, pivoted to the casing at f. The short end of this lever is provided with a roller f', which engages the surface of cam-wheel E³ for holding the clutch normally out of engagement. Lever F is in the form of a link or strap, as shown in Fig. 2, and at the clutch is provided with two screw-pins f², which work in a groove b in the movable head B. The long end of the lever is attached to a spring F', which is under tension and tends to close the clutch B B'. Roller f' is designed to drop into the cam or recess e² when the cam E³ is rotated, and when the roller is in the recess the spring will throw the lever and close the clutch B B'.

The parts so far described are inclosed in a dust-proof casing G, which is provided with arms or brackets G', by means of which the apparatus is hung from the running-gear or framework of a motor-carriage, for which the gear is primarily designed, although it will be understood this variable gear may be employed in other ways.

The motor end of the high-speed shaft is provided with a friction-pinion H. As shown in the drawings, this pinion is formed on the reduced portion of driving-clutch A'. This pinion is arranged to engage a similar friction-wheel H', which is mounted on the re-

versing-shaft I. The other end of the reversing-shaft is provided with a similar pinion H², which meshes with a similar friction-wheel H³, keyed on the driven end A⁵ of the main shaft, as shown in Fig. 3.

Reversing-shaft I is in two sections connected by miter-gears J, inclosed in a casing J'. Miter-gear J is employed to change the direction of rotation of shaft I, and hence causes the two sections of the high-speed shaft to rotate in opposite directions. Reversing-shaft I is mounted in eccentric sleeves k, working in bearings K, secured to the under side of casing G by suitable bolts, as shown in Fig. 3. The eccentric bearings are provided with arms connected by a rod, forming a rocker L, by means of which the sleeves are partially rotated. The rocker L may be moved by a lever in any suitable manner. In the normal position of the apparatus rocker L is held by a spring, (not shown,) so that the position of the eccentric sleeves k within the bearings K will hold the friction-pinions H' and H² out of mesh with pinions H and H³, respectively.

The position of the apparatus as shown in Figs. 1 and 4 is the position of rest. To start the motor-carriage or other apparatus driven through the variable gear, rack-bar E⁴ is shifted to the left, so as to rotate the shifting-shaft E in the direction of the arrows on disk E³ and through eccentrics e move slide S to the position illustrated in Fig. 5, so as to bring A², C', C², and A³ into mesh. The driving connection thus being from sleeve a through the low-speed shaft C and gear A³ to sleeve a', which, as above stated, is keyed to the driven end A⁵ of the high-speed shaft. During this operation clutch B B' is held out of engagement by lever F through the engagement of roller f' with the flat surface of cam-wheel E³, the cam e² having moved from the position of Fig. 4 to the position of Fig. 5. When wheels A², C', C², and A³ are fully in mesh, eccentrics e will be on dead-centers, as shown in Fig. 5, and hence any tendency of the slide to shift in the direction for separating said gears will be resisted at the eccentrics, and from this it will be seen that the disengagement of said gears can only be effected by operating the shifting-gear E' E². To obtain the intermediate speed, the movement of rack-bar E⁴ is continued in the same direction and the eccentrics actuating slide S will now move the slide in the opposite direction to the position shown in Fig. 6, thus throwing the pinions and gears just referred to out of mesh, and by continuing the movement to the position shown in Fig. 7 gears A², D', D², and A⁴ will be thrown into mesh, as shown in Fig. 7, the driving connection thus being from sleeve a through intermediate shaft D and gear A⁴ to sleeve a' on the driven end A⁵ of the high-speed shaft. During this shift roller f' still remains on the flat surface of cam-wheel E³, so that clutch B B'

is still held out of engagement, and in the shift from the position of Fig. 5 to that of Fig. 7 cam e^2 will have moved two steps forward in the direction indicated by the arrows 5 as shown in Figs. 6 and 7. In making the change from low speed to intermediate speed the eccentrics in moving slide S make one-half a revolution, and hence will be on dead-centers again, but on the opposite side, and 10 therefore slide S will be again locked in position, as above explained. To reach high speed, rack-bar E⁴ is moved still farther in the same direction, whereupon the eccentrics will now shift slide S in the opposite direction 15 again—that is, the direction in which it was moved for the low-speed connection, but to a lesser extent, as shown in Fig. 8. This movement brings the cam-surface e^2 beneath the roller f^2 , whereupon spring F' actuates lever 20 F and closes the high-speed clutch B B', the driving connection now being direct from sleeve a, which is the driving end of the high-speed shaft, to sleeve a', which is keyed to the driven end A⁵ of the high-speed shaft. 25 To reduce the speed from either the high or intermediate speeds or to bring the apparatus to the stopping position, rack-bar E⁴ is moved in the opposite direction, so that shaft E will rotate in the opposite direction to that indicated by the arrow in Fig. 1, the effect being 30 if the apparatus is connected for high speed to first move the lever F, so as to disengage clutch B B', then by continuing the movement of the rack-bar the intermediate-speed pinions and gears will be thrown into mesh and 35 immediately out of mesh, and then the low-speed connection will be thrown into mesh and immediately out of mesh if it is desired to bring the apparatus to a stop. It will be 40 understood that to stop at the intermediate speed the movement of the rack-bar will be arrested at the proper point.

In practice rack-bar E⁴ is shifted by a suitable controlling-lever with proper stopping-points for the different speeds; but since this forms no part of the present invention it is not illustrated nor described.

What I claim is—

1. In a variable gear, the combination with 50 the driving and driven shafts, of a clutch for making direct connection between said shafts, a lower-speed gear for connecting said shafts around said clutch, a lever for shifting one member of said clutch, a cam for controlling the movements of said lever, and a shifting mechanism for placing said lower-speed gear into and out of mesh with the driving and driven shafts, substantially as set forth.
2. In a variable gear, the combination with 55 the driving and driven shafts, of a clutch for making direct connection between said shafts, two lower-speed gears for connecting said shafts around said clutch, a lever for shifting one member of said clutch, a cam for controlling the movements of said lever, and a shifting mechanism for placing said

lower-speed gears into and out of mesh with the driving and driven shafts, substantially as set forth.

3. In a variable gear, the combination with the driving and driven shafts, of a clutch for making direct connection between said shafts, a lower-speed gear for connecting said shafts around said clutch, a lever for shifting one member of said clutch, a cam for controlling the movements of said lever, a reciprocating slide for placing said lower-speed gear into and out of mesh with the driving and driven shafts and means for shifting said slide, substantially as set forth.

4. In a variable gear, the combination with the driving and driven shafts, of a clutch for making direct connection between said shafts, two lower-speed gears, two shafts on which said gears are mounted and arranged parallel with the first-named shafts, for connecting said shafts around the clutch, a lever for shifting one member of said clutch, a cam for controlling the movements of said lever, and a shifting mechanism for placing said lower-speed gears into and out of mesh with the driving and driven shafts, substantially as set forth.

5. In a variable gear, the combination with the driving and driven shafts, of a clutch for making direct connection between said shafts, two lower-speed gears, two shafts on which said gears are mounted and arranged parallel with the first-named shafts, for connecting said shafts around the clutch, a lever for shifting one member of said clutch, a cam for controlling the movements of said lever, a reciprocating slide for placing said lower-speed gears into and out of mesh with the driving and driven shafts, and means for shifting said slide, substantially as set forth.

6. In a variable gear, the combination with the driving and driven shafts, of a clutch for making direct connection between said shafts, a lower-speed gear for connecting said shafts around said clutch, a spring-actuated lever for moving said clutch, a cam for controlling the movement of said lever, means for moving said cam to permit said lever to shift the clutch, and a shifting mechanism for placing said lower-speed gear into and out of mesh with the driving and driven shafts, substantially as set forth.

7. In a power-transmitting gear, the combination with a driving and a driven shaft, of a clutch for making direct connection between said shafts, a lever for shifting one member of said clutch, a cam for controlling the movements of said lever, and a reversing-gear for connecting said shafts around the clutch to rotate the driven shaft in a direction opposite to the direction of rotation of the driving-shaft, substantially as set forth.

8. In a power-transmitting gear, the combination with a driving and a driven shaft, of a clutch for making direct connection between said shafts, a lever for shifting one member of said clutch, a cam for controlling the move-

ments of said lever, and a reversing-gear for connecting said shafts around the clutch to rotate the driven shaft in a direction opposite to the direction of rotation of the driving-shaft, said gear comprising driven and driving pinions mounted independently, an intermediate gear for changing the direction of rotation, and means for shifting said reversing-gear into and out of mesh, substantially as set forth.

9. In a variable gear, the combination with the driving and driven shafts, of a clutch for making direct connection between said shafts, a lower-speed gear for connecting said shafts around said clutch, a lever for shifting one member of said clutch, a cam for controlling the movements of said lever, a shifting mechanism for placing said lower-speed gear into and out of mesh with the driving and driven shafts, and means forming part of the shifting mechanism whereby said lower-speed gear will be locked in operative position, substantially as set forth.

10. In a variable gear, the combination with the driving and driven shafts, of a clutch for making direct connection between the said shafts, two lower-speed gears for connecting said shafts around said clutch, a lever for shifting one member of said clutch, a cam for controlling the movements of said lever, a shifting mechanism for placing the said lower-speed gears into and out of mesh with the driving and driven shaft, and means forming part of the shifting mechanism whereby said lower-speed gears will be locked in operative position, substantially as set forth.

11. In a variable gear, the combination with the driving and driven shafts, of a clutch for making direct connection between said shafts, a lower-speed gear for connecting said shafts around said clutch, means for controlling said clutch, a reciprocating slide for placing said lower-speed gear into and out of mesh with the driving and driven shafts, means for shifting said slide, said means also constituting a locking means for locking said slide against movement when said lower-speed gear is in mesh with said driving and driven shafts, substantially as set forth.

12. In a variable gear, the combination with the driving and driven shafts, of a clutch for making direct connection between the said shafts, two lower-speed gears, two shafts on which said gears are mounted and arranged parallel with the first-named shafts for connecting said shafts around the clutch, means for controlling said clutch, a shifting mechanism for placing said lower-speed gears into and out of mesh with the driving and driven shafts, and means forming part of the shifting mechanism whereby said lower-speed gears will be locked in operative position, substantially as set forth.

13. In a variable gear, the combination with the driving and driven shafts, of a clutch for making direct connection between the said shafts, two lower-speed gears, two shafts on

which said gears are mounted and arranged parallel with the first-named shafts for connecting said shafts around the clutch, means for controlling said clutch, a reciprocating slide for placing said lower-speed gears into and out of mesh with the driving and driven shafts, means for shifting said slide, said means also constituting a locking means for locking said slide against movement when either of said lower-speed gears are in mesh with the driving and driven shafts, substantially as set forth.

14. In a variable gear, the combination with the driving and driven shafts, of a clutch for making direct connection between said shafts, a lower-speed gear for connecting said shafts around said clutch, means for controlling said clutch, a reciprocating slide for placing said lower-speed gear into and out of mesh with the driving and driven shafts, eccentrics for reciprocating said slide, said eccentrics being arranged so as to be on dead-centers when the lower speed is in mesh, and means for rotating said eccentrics, substantially as set forth.

15. In a variable gear, the combination with the driving and driven shafts, a clutch for making direct connection between said shafts, a lower-speed gear on each side of said driving and driven shafts, said lower-speed gears being mounted on shafts parallel with the first-named shafts for connecting said first-named shafts around the clutch, a lever for shifting one member of said clutch, a cam for controlling the movements of said lever, a reciprocating slide carrying the shafts of said lower-speed gears, and means for reciprocating said slide for simultaneously moving one lower-speed gear into mesh with the gears of the driving and driven shafts and the other out of mesh, substantially as set forth.

16. In a variable gear, the combination with the driving and driven shafts, a clutch for making direct connection between said shafts, a lower-speed gear on each side of said driving and driven shafts, two shafts on which said gears are mounted and arranged parallel with the first-named shafts for connecting said first-named shafts around the clutch, means for controlling said clutch, a reciprocating slide carrying the shafts of said lower-speed gears, and eccentrics for reciprocating said slide for simultaneously moving one lower-speed gear into mesh with the gears of the driving and driven shafts and the other out of mesh, and said eccentrics being arranged so as to be on dead-centers when either of the lower-speed gears are in mesh, substantially as set forth.

17. A driving-shaft provided with a pinion, a driven shaft in line therewith provided with a gear-wheel, a jaw-clutch for connecting and disconnecting said shafts, a lever for operating said clutch, a parallel speed-reducing shaft, a gear-wheel and pinion on said shaft which mesh respectively with the pinion and gear-wheel on the driving and driven shafts,

and operating means whereby said gears or said clutch can be brought into operative relation, and said means operating to prevent the simultaneous engagement of said gears and said clutch.

18. A driving-shaft provided with a pinion, a driven shaft in line therewith provided with two gear-wheels, a jaw-clutch for connecting and disconnecting said shafts, a lever for operating said clutch, a parallel speed-reducing shaft provided with a gear-wheel and pinion which mesh respectively with the pinion on the driving-shaft and one of the gear-wheels on the driven shaft, a second parallel speed-reducing shaft provided with a gear-wheel adapted to mesh with the pinion on the driving-shaft and a pinion adapted to mesh with the second gear-wheel on the driven shaft, and operating means whereby said gears or said clutch can be brought successively into operative relation, and said means operating to prevent the simultaneous engagement of either of said low-speed gears and said clutch.

19. A change-speed gear having in combination two end-to-end shafts, gear-wheels on said shafts, a clutch for connecting said shafts, a spring-actuated lever for operating said clutch, a cam for controlling the movement of said lever, a reciprocating slide, a speed-changing shaft carried by said slide and pro-

vided with a gear-wheel and pinion adapted to mesh with the gear-wheels on the first-named shafts, and a single means for simultaneously reciprocating said slide and rotating said cam, whereby, by a continuous movement of said means, said clutch and speed-changing gears are respectively moved into and out of engagement. 35

20. A change-speed gear having in combination two end-to-end shafts, gear-wheels on said shafts, a clutch for connecting said shafts, a spring-actuated lever for operating said clutch, a cam for controlling the movement of said lever, a reciprocating slide, two speed-changing shafts carried by said slide and each 40 provided with a gear-wheel and pinion adapted to mesh with the gear-wheels on the first-named shafts, and a single means for simultaneously reciprocating said slide and rotating said cam, whereby, by a continuous movement of said means, said clutch and speed-changing gears are successively moved into and out of engagement. 45 50

This specification signed and witnessed this 23d day of August, 1901.
